UNITED STATES PATENT OFFICE.

WILLIAM RANSOM, OF BROOKLYN, NEW YORK.

GAME APPARATUS.

SPECIFICATION forming part of Letters Patent No. 716,645, dated December 23, 1902.

Application filed June 19, 1902, Serial No. 112,286. (No model.)

To all whom it may concern:

Be it known that I, WILLIAM RANSOM, a citizen of the United States, residing at Brooklyn, Kings county, New York city, and New York State, have invented certain new and useful Improvements in Game Apparatus, of which the following is a full, clear, and exact description.

My invention relates to game-balls, and particularly to the construction thereof, adapted to be used in playing table-tennis and other games which require a light, flexible, and resilient ball.

The object of my invention is to provide a ball which may be used for playing games in the dark or at night.

The invention consists in the formation of a hollow ball, of celluloid or other flexible, elastic, or resilient material, in the interior of which is placed a suitable luminous material in order that the ball may be visible in the dark.

In the drawings, Figure 1 is an elevation of a ball embodying my invention. Fig. 2 is a relatively enlarged sectional view of a fragment of a ball embodying my invention.

This ball is preferably formed of a rather thin material—such as celluloid, rubber, or the like—which is transparent, semitransparent, or translucent to a sufficient degree to allow the light emanating from the luminous material inside to be visible from without. This ball is coated on the inside, as in-

dicated in Fig. 2, with a solution of luminous material or with a suitable luminous paint composed of some phosphorescent substance. The luminous material being applied to the interior coating of this spherical ball is held outward and securely in place against the surface of the ball by reason of its arched formation, so that there is no danger of the material being separated from the ball when the ball is being batted about or used as a ball of this character is customarily. There is therefore beside the ordinary adhesive force between the luminous material and the ball the strength of the material itself, which forms an arch. This advantage is considerable.

The use of this apparatus in a game or in any other way at night presents an extremely weird effect and affords a means for playing games with an apparatus of this character in the dark.

The ball is durable, and since it is preferably of light weight may be batted about, and is particularly adapted for the playing of table-tennis in the dark.

What I claim is—

A game-ball comprising a hollow translucent sphere formed of flexible material and having a coating of luminous material within the sphere and protected thereby.

WILLIAM RANSOM.
